UNITED STATES PATENT OFFICE.

WILLIAM R. MORRISON, OF DERRY, NEW HAMPSHIRE.

MAIL-BAG CATCHER AND DELIVERER.

No. 901,812.

Specification of Letters Patent.

Patented Oct. 20, 1908.

Application filed December 28, 1907. Serial No. 408,364.

To all whom it may concern:

Be it known that I, WILLIAM R. MORRISON, a citizen of the United States, residing at Derry, in the county of Rockingham, 5 State of New Hampshire, have invented an Improvement in Mail-Bag Catchers and Deliverers, of which the following is a specification.

My invention is an improvement in that 10 class of apparatus or devices designed for use on railways for receiving mail-sacks from a passing train and for delivering sacks thereto.

The invention is embodied in the construction, arrangement, and combination of parts hereinafter set forth, and illustrated in the accompanying drawings in which

Figure 1 is a side view of a portion of a mail-car with mail-bag hooks arranged and 20 suspended on either side of the doorway in the position they occupy when not in use. Fig. 2 is a cross section on the line 22 of Fig. 4, showing a crane for receiving mail-bags or pouches for the car-hooks shown in 25 Fig. 1. Fig. 3 is a vertical section of the car and a side elevation of the post arranged alongside the track and provided with my improved mail-bag receiving and delivering devices, the car-hook being 30 shown extended in the position required for receiving or delivering mail bags. Fig. 4 is a face view of the post provided with receiving and delivering cranes, and a yielding device adapted for relieving impact of 35 a mail-bag when being received. Fig. 5 is a plan view of a portion of the apparatus which is attached to a car, the same being shown in operative position and the side of the car being represented in section. Fig. 40 6 is a horizontal section on the line 6—6 of Fig. 4.

In the drawings, A and A' indicate duplicate devices, to wit, car-hooks which are 45 adapted for both receiving and delivering mail-bags or pouches. These consist (see especially Figs. 1 and 5) of levers 1 whose outer ends 2 are bent outward and curved, and supported by a diagonal brace 3, and a 50 spring hook 4, whose outer end is turned outward opposite end 2 and whose shank is turned inward and riveted to the body of

lever 1. Each of the levers 1 is provided with a hub 5 by which it is journaled on a horizontal shaft 6 extending across the doorway of the car and supported in eyes 7 fixed 55 to the car body, as shown in Fig. 5.

The rigid part 2 and the opposite outwardly curved spring 4 constitute a spring holder for supporting a mail-bag for delivery as indicated by dotted lines, Fig. 5, and 60 serve also as means for receiving a mail-bag, as will be further described. The hooks A and A', when not in use, are separated and hang vertically on the sides of the car-door as indicated in Fig. 1, thus leaving the 65 doorway entirely unobstructed, save by the shaft 6, which extends across it. Either of the hooks A or A' may be used alone, or singly, for both delivering and receiving mail-bags or pouches; but ordinarily, they 70 will be brought together and secured by a clasp 8, as shown in Fig. 5. This clasp or coupling forms a permanent attachment of one of the hooks and is adapted to be readily engaged with the other (see especially Fig. 75 1). Thus the two hooks A, A', when brought together, constitute what may be termed a double hook, which is operated as one device for receiving or delivering mail bags, according to the direction in which the 80 car is moving.

As shown in Figs. 3 and 6, a rod 9, which is in practice pivoted to the roof of the car, is provided at its lower end with an eye 9*, adapted to receive the inner ends of the hook 85 levers 1 and thus support the double hook in the horizontal position in which it is adapted to co-act with cranes on the post 11, to deliver and receive mail bags, as will now be described.

B and B' indicate devices which are 90 termed cranes, the same being fixed in horizontal position on the post 11 and separated from each other vertically by a distance sufficient to allow the hooks A and A' to pass freely between them. The upper cranes B project in opposite directions from the post 11 and are considerably longer than the lower cranes B', as shown in Fig. 4. The two sets of cranes are similarly constructed, 100 however, and consist of right-angular bars 12 whose shanks have lateral bends 12*

adapted to receive the post 11 between them, and are clamped or bolted to the same, as shown best in Fig. 6. The outer end of the bar 12 is curved laterally and supported by 5 a diagonal brace 13. A spring hook 14 is attached to the bar 12 on the outside and its free end is curved outward directly opposite the curved portion of the bar 12. Since the smaller bag-receiving hooks B' are identical 10 in construction, no special description of them is required.

The operation of my improved apparatus is as follows: Let it be supposed that the two hooks A, A', have been brought together 15 and secured as indicated in Figs. 3 and 5, and that it is desired to receive a mail-bag which has been suspended from one of the cranes B on the post as indicated by dotted lines, Fig. 6. The double car-hook is 20 swung upward into horizontal position and is held mechanically in that position by means of the pendent or swinging bar 9, as shown in Fig. 3. As the car moves in the direction of the arrow, Fig. 5, the hooks 25 pass between the cranes B, B', and the hook A', which is in advance, will engage and receive the mail-bag, the spring portion of the hook yielding to allow the mail-bag to pass in. The mail clerk or agent on the car 30 then detaches the swinging bar 9 from the hook levers 1 and the bag is swung into the car. Suppose, on the other hand, that it be desired to deliver a mail-bag from the double hook to the lower crane B' on the post 35 11. In such case, the mail-bag is suspended from hook A or hook A', according to the direction in which the car is moving; thus, if the car be moving in the direction indicated by arrow, Fig. 5, the mail-bag would 40 be suspended from the hook A', and the right hand lower crane B' would, in such case, obviously receive the mail-bag from the hook. When the train is running with considerable speed, it is obvious that the 45 mail-bag will be suddenly arrested by the crane, and to relieve the shock of impact, I provide a device 15, which is shown in Figs. 3 and 4. It consists of two woven-wire shields arranged at a considerable angle to 50 each other, and rigidly connected and spaced apart by rods 15^a, forming part of the suspending frame. The latter swings on a horizontal shaft 16 that is fixed to the post 11. A curved spring 17 is rigidly attached to 55 the shaft 16 and its ends are fixed to the post; see Fig. 4. It is obvious that not only the weight or inertia of the device 15, but also the spring resists lateral or swinging motion. It is apparent that a mail-bag suspended by the car-hook and received by 60 either of the hooks B', will strike upon the inclined adjacent side of the device 15, and that the latter will be thereby carried, that is to say, swung, on its pivot, as indicated

by dotted lines Fig. 4. In this manner, the impact of the mail-bag will be mostly taken up or relieved, so that injury to the same or to the crane, will be avoided.

Since there is considerable strain on the car-hooks in both delivering and receiving mail-bags, I have provided tension devices which consist of chains 18 and springs 19 connected and arranged as shown in Figs. 1, 3, and 5. That is to say, the springs are attached to eyes on each side of the doorway, 75 and the chains connected therewith are attached to eyes on the hook levers 1 adjacent to the outer ends of said levers. The combined length of the chains and springs is so proportioned that one of the springs will be 80 brought under tension, as shown in Fig. 5, when the hook is adjusted near the opposite side of the doorway, and consequently at that time the other chain and spring are slack, as indicated. When the two hooks are 85 separated and arranged in vertical position on opposite sides of the car doorway, as shown in Fig. 1, the chains and springs hang vertical as there shown. In practice, the hubs 5 of the hook levers 1 will be provided with 90 anti-friction balls to enable the hooks to be manipulated on the shaft 6 with greater ease.

What I claim is:

1. In an apparatus for the purpose specified, the combination, with a car and a transverse shaft arranged across its side doorway, of hooks adapted to slide on such shaft and projecting in opposite directions, and means for coupling such hooks together detachably, so that they may be used as a double hook, 100 or disconnected and arranged on the sides of the doorway when not required for use, substantially as described.

2. In an apparatus for the purpose specified, the combination, with a car and a horizontal shaft extending across its side doorway, of a hook mounted, and adapted to slide and rotate, on said shaft, and a spring-tension device comprising a chain and spring, the same being attached at one end to the 110 car body adjacent to the doorway, and at its opposite end to the hook of the catcher, the normal length of the said device being such that it is subjected to tension when the hook slides back part way of the length of the 115 shaft, as shown and described.

3. In an apparatus for the purpose specified, the combination, with a support arranged adjacent to a railway track, and a mail-bag catcher secured thereto, of an impact-reliever located below such catcher, and consisting of a frame on which a mail-bag is received, the same having a pivot on which it is adapted to swing in a vertical plane, substantially as described.

4. In an apparatus for the purpose specified, the combination, with a fixed support and a mail-bag catcher attached thereto of

an impact-reliever consisting of a device interposed in the path of a mail-bag and adapted to swing in a vertical plane, and a spring which resists the movement of the said device, substantially as described.

5. In an apparatus for the purpose specified, the combination, with a fixed support, and a mail-bag catcher secured thereto, of an impact-reliever comprising frames having

woven wire stretched thereon in two planes 10 which are at an angle to each other, as shown, the device being pivoted and adapted to swing in a vertical plane, substantially as described.
